MOLDING

Robert C. Schemmel, Union City, Ind.

Application October 26, 1931, Serial No. 571,195

7 Claims. (Cl. 155—184)

My invention relates to finishing moldings of the type used in trimming the exterior and interior of automobile bodies and the upholstery thereof, and this application is a continuation in part of my application Serial No. 560,437, filed August 31, 1931.

More particularly the invention contemplates a finishing molding provided with projecting fastening elements.

An object of the invention is to provide a molding of the character indicated in which the projecting fastening elements are securely united to the core of the molding so that, upon penetration of the fastening elements into a support, the molding will be positively held in applied position.

Another object is the incorporation in a molding of a stiffening element adapted to maintain the molding around any desired radius of curvature without puckering or buckling.

A further object is the provision of a molding in which fastening elements are carried by a continuous internal stiffening member, the latter being encased in a flexible core or body. An important object of the invention is to provide novel means for assembling the metallic fastening and stiffening elements and the flexible core or body.

A further object of the invention in one form of embodiment is to provide with the core a covering fabric secured thereto without the use of adhesives, so that, upon occasion, the covering fabric may be temporarily disassociated from the core to permit supplementary fastening elements to be passed through the core, after which the covering fabric may be restored to its normal covering position.

A still further object of the invention in one form of embodiment is to provide a molding including a stiffening wire carrying fastening elements received in a channeled and slotted core, the slit being so related to the channel that the wire will most easily be admitted to the channel through the slit and yet be prevented, when received in the channel, from being separated therefrom through the slit when the molding is being applied to a support.

Other and further objects of the invention will be more apparent as the description proceeds.

In the accompanying drawing which illustrates the invention in certain preferred forms of embodiment, and in which the same reference character designates the same part in the several views,

Figure 1 is a side elevational view of the invention in one form of embodiment;

Fig. 2 is a perspective view, with one end in cross section, of the molding shown in Fig. 1;

Fig. 3 is a similar view of a molding showing a modified type of core;

Fig. 4 is a similar view of a molding showing a further modified type of core;

Fig. 5 is a top plan view of a molding embodying a modified form of covering fabric;

Fig. 6 is a cross sectional view of the molding shown in Fig. 5; and

Fig. 7 is a cross sectional view of a molding showing a still further modified type of core.

Referring now to the drawing, the molding which forms the subject of this invention includes a flexible core 1, conveniently formed of molded or extruded rubber, woven or compressed paper, or any suitable relatively flexible material usually employed for this purpose. The core carries a pliable metallic stiffening element preferably in the form of a soft annealed iron wire 2. This wire is conveniently disposed longitudinally and continuously in the approximate center of the core 1, being contained in a recess or groove of suitable form there provided.

The element 2, in addition to its stiffening function, serves to maintain securely in position a plurality of fastening elements 3, in the form of sharp pointed shanks spot-welded, soldered or otherwise permanently secured to and made integral with the wire 2 in uniformly spaced alignment along one side thereof. The tacks commonly used with moldings of this general type are thus dispensed with.

The wire 2 is carried in the core 1 spaced upwardly from the bottom surface thereof, the fastening elements 3 being passed through the portion of the core between its recess which receives the wire 2 and the bottom surface of the core. The fastening elements 3 thus project from the bottom surface of the core and, when passed into a support, serve to maintain the core securely mounted on the support.

Figs. 2, 3, and 7 show three of several expedients contemplated by the invention by which the stiffening wire 2 is introduced into the core. As illustrated in Fig. 2, a kerf or slit 4 is cut from a side surface of the core 2 into the wire-receiving groove or recess at the center of the core, and in Fig. 3 a similar kerf 4a is shown extending from the upper surface of the core. In Fig. 7 the slit 4b is made tangent to the groove and the wire and preferably breaks the surface of the core along a line off-center of the groove. It will be obvious that in each of the variant forms of the invention the stiffening wire 2, with

its attached fastening elements 3, is incorporated in the core by merely expanding the sides of the kerf, introducing the assembly of elements 2 and 3 in such a manner that fastening elements 5 3 pass downwardly through the lower central portion of the core and the stiffening wire 2 seats snugly in the wire-receiving recess or groove. It is to be understood that the kerf or slit placing the interior groove or channel in communication with the outer surface of the core may be extended from the groove to the core surface at any angle, three desirable angles being shown merely by way of exemplification in Figs. 2, 3, and 7, respectively. In this connection 10 attention is invited to the form of the invention shown in Fig. 7 where the tangential relation of the groove and the kerf results in disposing an overlying lip 7 over the wire 2 which assists in holding the wire snugly in the groove and prevents movement of the wire from the groove 15 when the molding is being applied to a support.

Fig. 4 shows a further modification in which the wire-receiving groove consists in a trough or channel depressed from the upper surface 25 of the core. In this form of the invention I prefer to provide the wire-receiving channel in a depth sufficient to contain substantially all of the wire within the confines of the core, so that the covering fabric, hereinafter to be described, 30 when enveloped around the core, will not show any surface protuberance along the line of the stiffening wire.

In order to seal the surface of the kerf 4 or the surface depression shown in Fig. 4, and to 35 finish the outer surface of the molding, I prefer to encase the core in a strip of covering fabric 5, conveniently of textile material. The covering fabric shown in Figs. 1-4 inclusive consists of a strip of any suitable textile material of cotton 40 or the like, having any desired character of surface finish. Such a strip is secured to the core by an adhesive, the longitudinal edges of the strip being disposed in parallel relation along the bottom surface of the core close to and on opposite 45 sides of the projecting fastening elements 3.

Figs. 5 and 6 show a modified form of covering fabric which is associated with the core without the use of an adhesive. This form of fabric includes warp and weft threads of cotton or the like, and a series of spaced transverse or weft 50 threads of pliable metallic wire 6. I prefer to have the transverse wires 6 disposed in the interior or on the under side of the fabric, so as not to impair the ornamental character of the exterior surface finish thereof. The covering fabric of Figs. 5 and 6 is maintained around the core 1 by crimping the longitudinal margins over the bottom surfaces of the core. No adhesive is used, the stiffness of the transverse wire threads 55 6 being sufficient to maintain the wire fabric securely in its enveloped relation with the core.

It will be obvious that the wire cloth of Figs. 5 and 6 may be easily lifted and replaced. This capacity of the fabric is of value in many installations of molding, when it is necessary to supplement the regular fastening elements 3 with nails or tacks driven into portions of the core which are disposed around curves of short radius, or where it may be impossible to drive 60 one of the fastening elements 3 into a support at precisely the point where the fastening element 3 is provided. In such a case, the wire cloth covering is temporarily lifted from the core, the supplementary tack or nail is driven through the core, and the covering fabric is then restored to 65

its covering position, concealing the head of the supplementary nail or tack.

It is to be understood that the wire cloth type of covering fabric shown in Figs. 5 and 6 may be associated with the types of core shown in Figs. 5, 3, 4 or 7, or with any other type of core contemplated by this invention.

It will be appreciated that I have provided a molding having internal stiffening means for maintaining the molding in any straight or curved 10 condition and in which fastening elements are permanently and securely united to the molding core. I have also provided a convenient and simple method of associating the fastening elements and the core and of maintaining these elements 15 in their associated relation.

It is to be understood that I have shown the invention in certain preferred forms of embodiment merely by way of exemplification. The invention is capable of embodiment in other and 20 further modified forms, but all such modifications to the extent that they embody the principles of the invention as pointed out in the appended claims are to be deemed within the scope and purview thereof.

I claim:

1. A finishing molding including a flexible core provided with a continuous longitudinal kerf having an enlargement spaced inwardly from the external surface of the core, a stiffening wire contained within the enlargement having a plurality of spaced fastening elements permanently united to the wire and extending through the bottom surface of the core, and a strip of covering fabric secured around the outer surface of the core 35 concealing and holding together the lips of the kerf.

2. A finishing molding including a flexible core provided with a continuous longitudinal kerf and a continuous groove communicating therewith spaced inwardly from the bottom surface of the core, in combination with a stiffening wire contained within the groove having a plurality of spaced fastening elements permanently united to the wire and extending through the bottom 45 surface of the core, the kerf being tangent to the groove and breaking the outer surface of the core along a line off-center of the groove.

3. A finishing molding including a flexible core provided with a continuous longitudinal kerf and 50 a continuous groove communicating therewith spaced inwardly from the bottom surface of the core, in combination with a stiffening wire contained within the groove having a plurality of spaced fastening elements permanently united to 55 the wire and extending through the bottom surface of the core, a lip of core material integral with the core overlying the groove and the wire at a side of the kerf.

4. A finishing molding including a flexible core 60 provided with a continuous longitudinal kerf and a continuous groove communicating therewith spaced inwardly from the bottom surface of the core, in combination with a stiffening wire contained within the groove having a plurality of 65 spaced fastening elements permanently united to the wire and extending through the bottom surface of the core, the kerf being tangent to the groove and breaking the outer surface of the core along a line off-center of the groove, forming a 70 lip of core material integral with the core overlying the groove and the wire at a side of the kerf.

5. A finishing molding as claimed in claim 1 in which the covering fabric includes a plurality of interwoven transverse pliable metallic ele- 75

ments crimped around the outer surface of the core, whereby the covering fabric may readily be temporarily disengaged from the core to permit supplemental fastening means to be passed through the core.

6. A finishing molding as claimed in claim 1 in which the covering fabric includes a plurality of interwoven transverse wire elements crimped around the outer surface of the core, the longitudinal edges of the fabric being disposed in parallel relation along the bottom surface of the core on opposite sides of the projecting fastening ele-

ments, whereby the covering fabric may readily be temporarily disengaged from the core to permit supplemental fastening means to be passed through the core.

7. A finishing molding as claimed in claim 1 in which the covering fabric is a strip of wire cloth crimped around the outer surface of the core, whereby the covering fabric may readily be temporarily disengaged from the core to permit supplemental fastening means to be passed through the core. 5

ROBERT C. SCHEMMEL.
